Specification of Letters Patent. Patented Sept. 19, 1911.

Application filed March 11, 1908. Serial No. 420,424.

To all whom it may concern:

Be it known that I, LOUIS G. GREEN, a citizen of the United States, residing in Philadelphia, Pennsylvania, have invented 5 certain Improvements in Dispensing Apparatus, of which the following is a specification.

My invention relates to syrup holding and dispensing means employed in connection 10 with soda water fountains; the object of my invention being to provide a pumping structure for the purpose described which may be employed in connection with a syrup jar or other receptacle; such pumping structure 15 being capable of adjustment to regulate the amount of syrup or other liquid discharged, and automatically resetting itself for subsequent use.

The details of my invention will be pointed out hereinafter, reference being made to the accompanying drawings, in which:

Figure 1, is a sectional elevation of a soda water dispensing cabinet, showing my improved pumping structure in the position of use; Fig 2, is an enlarged sectional view of the pumping structure in the act of delivering a charge, and Fig. 3, is a view illustrating a detail of my invention.

In the accompanying drawings, 1 represents a soda water dispensing cabinet, having a counter 2, and beneath the same an ice chamber 3 and pockets 4 for the reception of syrup jars 5, which jars are susceptible of removal in the usual or ordinary manner, 25 as indicated by dotted lines. Covering the syrup jar is a plate 6, of marble, metal, or other suitable material, which plate supports the mechanism forming the improved pumping structure comprising my invention. The plate completely covers the jar and rests in the inclined position shown, the front slab 7 of the cabinet being recessed at 8 for the front edge of said plate.

The pumping structure comprises a cup-like member 10 having arms 10^a connected to a tubular stem 11, the upper end of which is threaded into a collar 12 and secured in position relatively to said collar by means of a lock nut 13. To facilitate cleansing, the tube 11 is made with openings 11^a. The syrup jars have pockets or recesses 14 in the bottom of the same to receive the cup-like member 10. Carried by the plate 6 is a mem-

ber 15, to which the collar 12 is secured; such member also having integral therewith a delivery spout 16. Disposed within the cup-like member 10 is a piston 17 carried by a rod 18 which passes through the tubular stem 11 and member 15 and is threaded into a suitable knob or handle 19. This knob has an elongated hollow stem 20 passing into the member 15 as shown, the hollow portion providing for the reception of a suitable spring 21, whereby the piston 17 carried at the lower end of the rod 18 is maintained normally in the upper part of the cup-like member 10; the arms 10^a of said member being provided with stops 22 to limit the upward movement of the piston.

The delivery pipe for the syrup is indicated at 25 and this pipe extends from the cup-like member 10 to the member 15, into which it is threaded at 26, said pipe also passing through the piston 17 and one of the supporting arms 10^a of the cup 10 in the manner shown and thereby serving to prevent the piston turning when the structure is operated. The bottom 27 of the cup-like member is threaded into the same in the manner shown; and is provided with a notched boss 28 on its under side to facilitate the engagement and disengagement of these parts, which may be accomplished by the aid of an ordinary screw driver. The arms 10^a have lugs 29 which serve to guide and center the same in the pocket or recess 14 of the jar.

To limit the downward movement of the rod carrying the piston and thereby limit the stroke of the piston and the amount of syrup discharged, the member 15 is provided with an adjustable sleeve 30 which surrounds the stem 20 of the knob in the manner clearly shown. When said sleeve is set all the way in as illustrated in Fig. 2, operation of the piston 17 will cause the delivery of a full charge of syrup, fruit juice, or other liquid within the jar. When extended, however, any distance, such for instance as indicated in Fig. 3, said sleeve will serve to limit the depression of the piston by its engagement with the knob 19, and hence materially limit the amount of syrup discharged.

It will be observed in reference to my structure that it is wholly self-contained;

that the delivery spout is fixed with respect to the fountain structure so that it is not necessary to shift the glass relatively to said delivery spout when operating the pump; 5 that said pump carries its own well, and that the outlet pipe of the syrup passes through the piston and one of the supporting arms of the cup-like member 10, so as to guide the same and prevent turning of 10 said piston. By disposing the front slab at an angle as shown with the syrup jars at the same angle, extra space is provided on the working shelf for glasses, &c.

It will be noted that the arms 10^a of the 15 supporting structure serve to guide the piston into its chamber formed by the cup-like member 10. In other pumps the piston must usually be raised to a point above the chamber where the inlet thereto is uncovered 20 at the end of the upward stroke of the piston. In some cases the piston is lifted entirely out of the piston chamber and on attempting to reenter same on the downward stroke is apt to move out of alinement 25 and strike on the edge of the chamber, thereby damaging the piston.

A further feature of my invention consists in the fact that the means for adjusting the length of stroke of the piston and 30 consequently the amount of syrup dis-

charged, are located wholly exterior of the syrup jar and its cover, and consequently such adjustment can be made without removing the pumping structure from the syrup jar.

35

I claim:

The combination, in a dispensing apparatus, of a jar having a well or depression in the bottom of the same, a tubular member, a delivery spout, a cup secured to said tubular member and fitting within the well of the syrup jar, a rod movable within said tubular member, a piston carried by the same and arranged to operate within the cup, arms carried by the cup for guiding the piston, a handle to which said rod is attached, means for returning the rod to its normal position after depression, an outlet tube leading from said cup and connected to the delivery spout, said tube passing through the piston and 45 one of the arms of the cup, and means for limiting the upward movement of the piston.

In testimony whereof, I have signed my name to this specification, in the presence of two subscribing witnesses.

LOUIS G. GREEN.
